UNITED STATES PATENT OFFICE

2,605,436

ELECTRIC INCANDESCENT LAMP

Joseph E. Stone, Cleveland Heights, and John O. Geissbuhler, South Euclid, Ohio, assignors to General Electric Company, a corporation of New York

Application July 1, 1950, Serial No. 171,768

5 Claims. (Cl. 313—113)

1

Our invention relates in general to electric incandescent lamps, and more particularly to a reflector type incandescent lamp adapted to project a concentrated light beam of high intensity.

Reflector type electric incandescent lamps of the so-called "sealed beam" type described and claimed in U. S. Patent 2,148,314—D. K. Wright, and comprising glass reflector and cover glass sections fusion-sealed together to form the lamp envelope and having a concentrated light source located at or closely adjacent the focus of the reflector are well known in themselves and are in widespread use in many applications as, for example, in vehicle headlights, airplane landing lights, floodlights and spotlights, to mention a few. Another useful application is for a small portable spotlight or as a spotlight for general service, such as store lighting and display, for instance, which is operable from a commercial power line and is capable of projecting an intense light beam over an extended distance. A lamp suitable for such spotlight use is described and claimed in copending U. S. application Serial No. 171,726, R. E. Smith, filed of even date herewith, and assigned to the assignee of this invention, now U. S. Patent No. 2,597,681, issued May 20, 1952. The present application relates to an improvement over the lamp construction disclosed in the aforesaid copending application.

It is an object of our invention to provide an electric incandescent lamp of the above-mentioned "sealed beam" type which will produce a concentrated high intensity light beam which is of more or less circular cross section with a central hot spot of maximum beam candle power and which uniformly tapers off in intensity to the outer edges of the beam so as to be free of dark spots therein.

Another object of our invention is to provide a relatively high wattage electric incandescent lamp of the above character which is operable from a commercial or household power source and which will produce a concentrated high intensity light beam of more or less circular cross section and of great projection distance.

Still another object of our invention is to provide an electric incandescent lamp of the above character having a three-segment filament and which is of simplified and rugged construction and is capable of withstanding impacts or sudden jars without breakage of the filament or distortion thereof which would result in premature filament burn-out and shortened lamp life.

A further object of our invention is to provide an electric incandescent lamp of the above char-

2

acter having a filament which is concentrated about the focal point of the focusing reflector of the lamp envelope and which is effectively supported to protect it against physical shock and maintain it in proper position substantially free from sagging during operation.

According to one aspect of the invention, a coiled-coil tungsten wire filament of proper length and resistance for operation from an ordinary commercial or household power line of from 110-120 volts, for instance, is divided into three individual leg portions or segments the center one of which is longer than the two end segments, which segments are disposed in a single plane and at an acute angle to one another to form an N or Z shape, and the so-formed filament is arranged substantially symmetrically about the focal point of the focusing reflector of a "sealed beam" type lamp such as disclosed in the above-mentioned U. S. Patent 2,148,314, with the plane of the filament located in an axial plane of the reflector axis and the center segment of the filament extending along the axis of the reflector.

According to another aspect of the invention, the above-described N or Z-shaped filament is firmly supported in place in the lamp envelope to withstand physical shock and maintain its initial position free from sagging in an axial plane of the lamp reflector by having its opposite ends clamped or otherwise securely fixed to the inner ends of rigid inlead conductors and by being additionally supported intermediate its length, at the bights or connecting loops between adjacent coil legs or segments, by supplementary supports anchored to an insulating bridge fastened across the rigid inlead conductors.

Further objects and advantages of our invention will appear from the following detailed description of species thereof and from the accompanying drawing.

In the drawing, Fig. 1 is a sectional view of an electric incandescent lamp comprising our invention; Fig. 2 is an enlarged perspective view of the amount structure of the lamp shown in Fig. 1; and Fig. 3 is an enlarged perspective view of a modified mount structure according to the invention.

Referring to the drawings, the electric incandescent lamp according to the invention is of the "sealed beam" type disclosed and claimed in the above-mentioned U. S. Patent 2,148,314, D. K. Wright, and comprises a sealed glass envelope or bulb 1 consisting of a preformed pressed glass reflector section 2 and a preformed pressed glass

55 cover section 3 fusion-sealed together at their

peripheries, as indicated at 4. The cover section 3 may be made of clear glass, or it may be stippled or otherwise rendered light-diffusing. The inner surface 5 of the reflector section 2 is provided with a reflecting coating 6 and is formed of substantially paraboloidal shape, with a focal length of approximately $1\frac{1}{8}$ inch or thereabouts, so as to redirect light rays from a concentrated light source at the focus of the reflector 6 into a long beam of substantially parallel rays. The reflecting coating 6 may be of aluminum, silver or other similar light-reflective material.

Mounted on the rear outer side of the reflector section 2 at the region of the apex or center thereof is a base structure 7 of the side-prong type shown and described in U. S. Patent Application Serial No. 171,766, Geissbuhler et al., filed of even date herewith and assigned to the assignee of the present invention, and comprising a pair of terminal contacts 8, 8 in the form of metal prongs or contact blades which are rigidly secured and electrically connected at one end to the closed nipple ends 9 of respective metal ferrules or thimbles 10, 10. The ferrules 10, 10 are formed of a suitable metal which will readily "wet" and adhere to the glass of the reflector section 2 and they are provided with skirt portions 11 which are feathered to knife edges embedded and fused in the glass of the reflector section 2 around respective openings or passageways 12 through the wall thereof. The contact prongs 8 are preferably secured to the nipple ends 9 of the ferrules 10 by being wrapped therearound and soldered thereto, and as shown, they extend laterally of the reflector section 2 and project outwardly from the side of a generally cylindrical metal cup or cap 13 which is securely fastened to the base end or apex of the reflector section to enclose the projecting ferrules 10. The contact prongs 8 are firmly held in spaced relation, insulated from each other and from the metal cap 13, by an insulative spacer block 14 of porcelain or other suitable insulating material which projects through an opening 15 in the cylindrical wall of the metal cap 13 and is slotted, as indicated at 16, to receive and hold the prongs 8 therein. The envelope 1 is provided with an exhaust tubulation 17 communicating with the interior of the envelope through an exhaust opening 18 in the envelope wall at the apex of the reflector section 2. After exhaustion of the envelope through the tubulation 17 and, if desired, the introduction of a suitable gas filling such as nitrogen or argon, the tubulation 17 is sealed or tipped off as indicated at 19.

Mounted within the envelope 1 and supported solely from the metal ferrules 10, 10 is a lamp mount structure 20 according to the invention and comprising a pair of rigid wire inleads 21, 21 secured and anchored at their outermost ends within the nipples 9 of the ferrules, as by solder 22 as shown. The inleads 21, 21 are made of any suitable material, such as molybdenum, nickel or iron, which will withstand the heat to which they are subjected during lamp fabrication and operation, and they are of large enough diameter to render them relatively rigid. In the particular case illustrated, for example, the inleads 21, 21 are made of 50 mil diameter nickel-plated iron wire. From the ferrules 10, 10, the inleads 21, 21 extend in more or less parallel spaced relation ($\frac{1}{8}$ inch apart in the particular case shown) through the openings 12, 12 in the wall of the reflector section 2 and into the envelope 1. The inleads

21, 21 extend approximately parallel to and lie in a plane containing the axis $x-x$ of the reflecting surface 6, and they are substantially symmetrically disposed on opposite sides of said axis. Adjacent their inner ends, the inleads 21, 21 are symmetrically offset inwardly toward each other, by means of inwardly bent portions 23, 23, to provide inwardly offset inner ends 24, 24 lying in the same plane as the outer portions 25, 25 of the inleads and extending substantially parallel to the reflector axis $x-x$. The inwardly bent portions 23, 23 of the inleads, along with the inwardly offset inner ends 24, 24, thus together constitute inwardly directed and confronting inner end portions of the inleads 21, 21. At their innermost ends, the inleads 21, 21 are suitably connected, as by clamping or welding, to the terminal ends or extremities of an electric energy translation element or filament 25. In the particular case shown, the innermost ends of the inlead offset portions 24, 24 are flattened and reversely bent back upon themselves to form hooks or clamps 26 located substantially in the plane of the inleads 21, 21 as well as in the focal plane of the reflector, within which hooks the filament ends are clamped to thereby securely fix the filament ends and fixedly position and rigidly support them from the inleads in the plane of the latter, and provide a good electrical connection therebetween. The filament 25 comprises a fine tungsten wire of suitable design or size, i. e., length and diameter, to operate at the particular voltage and wattage for which the lamp is designed, for example, from a conventional commercial or household power line of from 110-120 volts and at a wattage of say 100 to 300 watts, for instance, and it is coiled throughout its length into small or minute minor coils and then into larger or major coils to form a coiled-coil wire. By employing a filament in the form of a coiled-coil wire, the over-all length of the filament body is shortened to impart ruggedness thereto and concentrate it as much as possible.

The coiled-coil filament 25 according to the invention is divided into three straight leg portions or segments 27, 28, and 29 defined by the larger or major coils of the filament, which segments are arranged at an acute angle relative to each other to form an N or Z shape and are joined at the apices of the N or Z by connecting loops or bights 30, 31 (Fig. 2), each formed by opening up one of the major or larger coil turns of the coiled-coil filament wire. The angle of divergence or spread of adjacent segments of the filament 25 is preferably made relatively small or narrow to concentrate the filament about the focal point F of the reflecting surface 6, and the three segments 27, 28, 29 are disposed in a plane containing the axis of the reflector, and preferably in that axial plane thereof which includes the inleads, in order to present the smallest possible projecting area to obstruct the light rays reflected from the central regions of the reflecting surface 6 toward the front of the envelope.

The outer segments 27, 29 of the filament 25 according to the invention are made shorter than the center segment 28, and the lengths of the said center segment and the two outer segments, and the angle of divergence of the latter from the center segment 28 are so proportioned as to produce the optimum desired beam pattern and locate the end legs or extremities 32 of the filament at points substantially midway of the length of the center segment 28 so as to lie opposite one another laterally of the center segment. In general, we have obtained good results by making the

length of the outer or end segments 27, 29 at least 40 per cent, but not more than 90 per cent, of the length of the center segment 28, and preferably about half as long as the center segment. In accordance with the invention, the N or Z-shaped filament 25 is mounted substantially symmetrically or centered about the focus of the reflecting surface 6 with the center segment 28 extending axially of the reflector axis $x-x$ and its midpoint located at the focus F of the reflecting surface.

The filament 25 is additionally supported at the bights 30, 31 thereof to maintain the apices of the filament substantially in the plane of the inleads 21, 21 and hold the filament in place against sagging during operation, by a pair of intermediate supports 33, 34. The said intermediate supports may be made of 12 mil diameter molybdenum wire, for instance, and they are each embedded at one end in the glass rod 35 of an insulative bridge or cross bar 36 which is fastened across the two inleads 21, 21 in a position inwardly of the filament, by pairs of support wires 37, 37 extending from the opposite ends of the glass rod 35 and welded or otherwise secured to the inleads to thereby rigidly tie the latter together. One of the intermediate filament support wires 34 is longer than the other support wire 33 and it extends from the glass insulator rod 35 in a direction transversely to the plane of the inleads 21, 21 as indicated at 38 and is then bent to extend outwardly of the reflecting surface 6 in a direction more or less parallel to or at a slight angle to the axis $x-x$ of the reflector, as indicated at 39. The free end of the support wire 34 is bent inwardly toward the filament to form an inturned arm 40 formed with a U-shaped loop or hook 41 within which the upper bight 39 of the filament is loosely hooked to thereby position and support the filament at its outer apex against sagging. The other or shorter support wire 33 extends from the glass insulator rod 35 in a direction outwardly of the reflector 2 substantially parallel to the reflector axis $x-x$ and in the plane of the filament 25, and is likewise provided at its free end with a U-shaped loop or hook 42 within which the lower bight 31 of the filament is loosely hooked to thereby position and support the filament at its inner apex against sagging. As shown, the hooks 41, 42, on which the filament bights 30, 31 are respectively hooked, are located substantially in the common plane of the inleads 21, 21 and filament 25 to thereby position and support the filament at its apices, from sagging, substantially in the plane of the inleads 21, 21.

The filament bights 30, 31 are loosely hooked or looped over the U-shaped hooks 41, 42 of the support wires 33, 34 in order to permit a limited amount of free movement of the filament bights in the hooks longitudinally of the filament segments during operation of the lamp to compensate for the expansion and contraction of the filament segments, and also in order to space the filament segments, at the apices of the filament, sufficiently far apart to prevent contact therebetween when the lamp is subjected to a physical shock. As shown in Fig. 2, the U-shaped hooks 41, 42 are sufficiently deep and practically parallel to one another to thereby function as guiding means for the apices of the filament and prevent displacement or disengagement of the filament from the support hooks 41, 42 when heated during the operation of the lamp. Preferably, the intermediate filament support wires 33, 34 are initially set to exert a sufficient pull on the apices of the filament in opposite directions lengthwise

of the inleads 21, 21 so as to draw the filament segments more or less taut between their points of support, thus tending to keep the filament substantially taut and free from sagging in the plane thereof during lamp operation so as to maintain the light rays in proper focus relative to the reflector. The intermediate supports 33, 34 are sufficiently rigid to prevent permanent displacement of the filament from its initial position, but the slight resiliency of these supports permits the filament to move slightly when the lamp is subjected to a physical shock so that there is less danger of filament breakage than would be the case if all strains had to be taken up by each individual segment of the filament.

The modified mount structure 43 illustrated in Fig. 3 differs from that shown in Figs. 1 and 2 only in the form of the end legs 45 of the filament 44 which in this case are arranged so as to extend substantially along the respective axes of the outer filament segments 27, 29, and in the form of the inleads 46, 46 which are bent inward at their inner ends to form inwardly directed confronting inner end portions 47, 47 which extend toward the reflector axis $x-x$ and lie in the same plane as the main inlead portions 46, 46. The innermost ends of the inleads 46, 46 are formed with hooks 48, 48 within which the filament end legs or extremities 45 are clamped substantially along the respective axes of the two outer segments 27, 29 of the filament, some of the minor coils of the single coiled end portions 45 of the filament being crushed between the two sides of the inlead hooks 48 in the same manner as in Figs. 1 and 2.

The relatively small angle of divergence or spread of the filament segments 27, 28, 29, coupled with the coiled-coil construction of the filament, serves to concentrate the filament at and adjacent the focal point F of the reflector 6 sufficiently so as to produce a light beam which is of substantially circular or slightly elliptical section and which is of maximum intensity at the center thereof and uniformly tapers off in intensity to the outer edges of the beam so as to be free of dark spots or areas of lower intensity in the central regions of the beam. The center segment 28 of the filament, because of its disposition extending along the axis $x-x$ of the reflecting surface 6, produces an intense spot of light at the very center of the beam, while the two outer segments 27 and 29 produce offset spots of light which are located slightly to either side of the center of the beam depending upon the spread of the segments. However, because of the shorter length of the outer filament segments 27, 29 as compared to the center segment 28, and their location to one side of the focus F of the reflector, the offset spots of light produced by the outer segments 27, 29 are not as bright as the central spot produced by the center segment 28. Consequently the light intensity or beam candlepower tapers off or diminishes more or less uniformly from the center of the beam, resulting in a beam which is of excellent beam candlepower distribution characteristics and which, when further coupled with a lightly stippled or otherwise slightly diffusing cover glass 3 to smooth out the slight irregularities in the beam, provides an exceptionally smooth beam of uniform graduated beam candlepower highest at the center and gradually decreasing outwardly thereof. This is in marked contrast to the beam produced by a V-shaped coiled-coil filament mounted symmetrically about the

focus F of the reflector so as to lie in an axial plane of the reflector with its apex pointed outward and located on the axis of the reflector, such a beam being characterized by a darkened spot at the center of the beam due to the fact that the two diverging legs of the V filament produce bright spots located slightly to either side of the center of the beam.

From the above description, it will be apparent that we have provided a "sealed beam" type of lamp for operation from a power line of any suitable voltage, such as a conventional commercial or household power line of 110 to 120 volts for example, and which will operate to project a concentrated and substantially circular light beam of high intensity, and of excellent beam candlepower distribution characteristics, for a relatively great distance. The filament is composed of three coiled-coil segments or portions which are arranged in the shape of an N or Z and which concentrate the filament so as to approximate the desired point source of light for use with the focusing reflector, and an effective supporting arrangement is provided to support the filament rigidly at its terminal extremities as well as at points intermediate its end to thereby protect it against physical shock and maintain all portions thereof substantially in their initial position, free from sagging, in an axial plane of the reflector during all operating conditions throughout the life of the lamp. Moreover, the construction and arrangement of the filament segments 27, 28, 29 so that the filament end legs or extremities 32 or 45 are located opposite one another approximately midway of the length of the center segment 28, enables the use of inleads 21 or 46 of substantially identical form or shape, thus minimizing and simplifying the manufacturing operations and the number of parts required for the mount structure according to the invention.

Although preferred species of our invention have been disclosed, it will be understood that the invention is not to be limited to the specific construction and arrangement of parts shown, but that they may be widely modified within the spirit and scope of our invention as defined by the appended claims.

What we claim as new and desire to secure by Letters Patent of the United States is:

1. A spotlight comprising a focusing reflector for producing a long beam of parallel rays, a pair of rigid inlead conductors extending into the interior space of said reflector and having their inner ends disposed laterally on opposite sides of the axis of said reflector and substantially in an axial plane thereof, a coiled-coil filament mounted within said reflector on said conductors and comprising three individual segments interconnected at their ends and arranged in substantially an N-shape, the opposite ends of said filament being connected to and supported in said plane by the inner ends of said conductors, and means for additionally supporting the filament at the junctions between the said segments to hold it substantially centered about the focal point of said reflector and substantially in said plane with the center segment of the filament extending axially of the reflector and the midpoint of said center segment located substantially at the focal point of the reflector.

2. An electric incandescent lamp comprising a sealed envelope having a focusing reflector for producing a long beam of parallel rays, a pair of rigid inlead conductors sealed through the wall of said envelope and extending into said envelope with its inner ends disposed laterally on opposite sides of said reflector and substantially in an axial plane thereof, a coiled-coil filament mounted within said envelope on said conductors and comprising three individual segments interconnected at their ends and arranged in substantially an N-shape, the opposite ends of said filament being connected to and supported in said plane by the inner ends of said conductors, and means for additionally supporting the filament at the junctions between the said segments to hold it substantially centered about the focal point of said reflector and substantially in said plane with the center segment of the filament extending axially of the reflector and the midpoint of said center segment located substantially at the focal point of the reflector.

3. An electric incandescent lamp comprising a sealed envelope having a focusing reflector for producing a long beam of parallel rays, a pair of rigid inlead conductors sealed through the wall of said envelope and extending into said envelope in the general direction and on opposite sides of the axis of said reflector with its inner ends disposed substantially in an axial plane of and in the focal plane of said reflector, a coiled-coil filament mounted within said envelope on said conductors and comprising three individual segments interconnected at their ends and arranged in substantially an N-shape, the opposite ends of said filament being connected to and supported substantially in said planes by the inner ends of said conductors, and means for additionally supporting the filament at the junctions between the said segments to hold it substantially centered about the focal point of said reflector and substantially in said axial plane with the center segment of the filament extending axially of the reflector and the midpoint of said center segment located substantially at the focal point of the reflector.

4. An electric incandescent lamp as set forth in claim 1 wherein the outer segments of the said filament are of shorter length than the center segment thereof.

5. An electric incandescent lamp as set forth in claim 3 wherein the said additional support means comprises an insulative bridge fastened across the said inlead conductors and carrying support wires having hooked ends on which the junctions between the filament segments are hooked.
